COIN CONTROLLED MACHINE

Burns S. Watling, Chicago, Ill., assignor to Watling Manufacturing Company, Chicago, Ill., a corporation of Illinois

Application April 30, 1934, Serial No. 723,067

4 Claims. (Cl. 194—1)

This invention relates to coin-controlled apparatus of the type having an operating mechanism housed within a casing and actuated by an actuating member which is normally locked by a latch which is adapted to be disabled by coin-controlled means to permit the operating mechanism to function. In this type of machine, the actuating member located within the casing is connected to an external operating lever or handle.

In the operation of vending machines and similar coin-controlled mechanisms, unscrupulous persons frequently attempt to cheat the machines. Various methods have been employed in attempting to actuate the operating mechanism without inserting a coin. Sometimes the external operating handle is struck with considerable force and, with machines heretofore in use, this has frequently resulted in damage to the actuating member or to that portion of the operating mechanism which receives the impact of the actuating member. Also attempts have been made to disable the latch by a sudden and swift initial movement of the operating handle.

The main objects of this invention are to provide a coin-controlled apparatus having an improved form of actuating member for the operating mechanism; to provide improved means for cushioning the impact of the actuating member against the operating mechanism so as to prevent damage to these parts when the handle is struck with great force; and to provide an improved auxiliary latch to limit the stroke of said actuating member when an attempt is made to disable or break the main latch.

An illustrative embodiment of this invention is shown in the accompanying drawings, wherein:

Fig. 1 is a fragmentary side elevation of a coin-controlled mechanism, part of the casing being broken away.

Fig. 2 is a view in front elevation of the parts shown in Fig. 1, and showing also the operating handle and improved actuating member.

Fig. 3 is a side elevation, taken from the right of Fig. 2, and showing certain parts in dotted outline; a portion of the casing being cut away to show the actuating member.

Fig. 4 is a side elevation of the actuating member and its support as viewed from the inside of the casing; part of the adjacent wall of the casing being shown, and part of the operating handle being shown in dotted outline.

Fig. 5 is a section, taken on the line 5—5 of

In the construction shown in the drawings, the invention is applied to a well known type of vending machine but this improvement is equally applicable to a large number of different coin-controlled machines. The drawings illustrate only those portions of the vending machine which will be of assistance in describing the improvement.

In the construction shown, the vending machine comprises the usual casing 1 having a front wall 2, side walls 3 and 4, respectively, and top and bottom 5 and 6, respectively. Mounted within the casing, is the operating mechanism which includes a bell crank lever 7 pivotally supported on a pin 8 secured to an upright bracket 9. One arm of the bell crank is provided with a pivoted finger 10 which carries a roller 10.1 adapted to coact with a member 10.2 of the vending or other mechanism (not shown). A spring 11 connected to the lever 7 and bracket 9 normally holds the lever 7 in its retracted position against a stop 12. Formed on the lever 7, is a full-stroke ratchet 13 adapted to cooperate with a pivoted, spring-held dog 14 on the bracket 9 to compel a complete shift of the lever before it can be returned to normal position. Mounted on the forward end of the bell crank 7 is a pin 15 adapted to coact with the actuating means hereinafter described.

The operating mechanism is normally locked by a latch bar 16 pivotally secured to the bracket 9 by a pin 17. Formed in the rear edge of the latch bar 16, is a notch 18 for receiving a lug 19 on the bell crank 7 to prevent a complete movement of the bell crank when the latch has not been disabled by the proper coin. The latch bar is normally urged rearwardly by a spring 20 connected to the bracket 9 and to a hook 21 formed on the upper end of the latch bar.

Formed on the inner edge of the latch bar, is a cam portion 22 adapted to coact with the lug 19 for holding the latch retracted, as shown in Fig. 1, when the bell crank 7 is moved to its uppermost position. The construction is such that the latch permits a limited movement of the lever 7 without the use of a coin, i. e., the lever 7 may move downwardly until the lug 19 rides into the notch 18. To permit a complete operation of the lever 7, the latch 16 must be retained in its retracted position and this is accomplished by the coin-controlled means.

The coin-controlled means includes a coin head or chute 23 rigidly secured to the upper portion of the bracket 9. This chute comprises a rear channel member 24 having a front plate 25 secured thereto by screws 26. The upper por-

tion of the channel member 24 projects above the top of the casing to form the usual neck 27 having a detachable front plate 28 provided with a coin inlet opening 29.

5 An inserted coin will pass downwardly through the chute and will be arrested in operative position by the toe of a spring-pressed dog 30, which is pivotally connected by a pivot pin 31 to a lug 32 on one side of the chute. The dog 30 is 10 normally held in the position shown in Fig. 2 by a spring 33 connected to the chute by a pin 34. This spring yieldingly retains the dog 30 in position to arrest an inserted coin.

Formed in the front plate 25 of the chute, 15 adjacent the dog 30, is an opening 35 which is slightly smaller than the coin for which the machine is intended. This opening is arranged so that, if any slug or coin smaller than the opening is inserted into the chute, it will be ejected 20 through the opening by means of a plunger 36 which is mounted on the upper end of the latch bar 16 and which is adapted to be projected through an opening 37 in the rear channel member 24. As the latch shifts from its normal position, shown in Fig. 1, to its locking position under the action of the spring 20, during the initial movement of the bell crank 7, the plunger 36 is forced forwardly through the aligned openings 37 and 35 in the coin chute. If a coin of proper 25 size is in operative position in the coin chute, it will stop the plunger 36, so as to prevent the latch 16 from being shifted to its locking position under the action of the spring 20, and the operative movement of the bell crank 7 may 30 then be completed.

The inserted coin is pushed downwardly from 35 operative position by a lug 42 which projects through a pair of arcuate slots 43 and 44 formed in the front and back walls, respectively, of the chute. The lug 42 is mounted on an arm 45 which is pivotally secured to the chute by a pin 46 and it is actuated by a link 47 which is pivotally secured to the arm 45 and bell crank 7 by pins 48 and 49, respectively. The link 47 holds 40 the arm 45 in the normal position shown in Fig. 2 with the lug 42 located adjacent a shoulder 50 on one edge of the coin slot. This shoulder deflects the inserted coins so that they will pass around the lug 42 and between this lug and the 45 opposite edge of the slot.

The initial movement of the bell crank lever 55 7 will not depress the arm 45 sufficiently to bring the lug 42 into engagement with the coin in operative position in the coin chute but, when a coin of proper size is located in operative position, the complete shift of the bell crank 7 will swing the arm 45 downwardly so that the lug 42 will engage the coin in operative position and force it downwardly past the dog 30 which is thereby retracted against the action of the spring 33.

In the form shown, the lower portion of the chute is provided with means for arresting two coins below the operative position, and a window (not shown) is placed in the front wall of the casing so that the owner of the machine may see the arrested coins for the purpose of detecting slugs which might be used by unscrupulous persons. The arresting means comprises a lever 60 51 which is pivotally connected to the rear wall of the chute by a pin 52 and normally urged toward the coins by a spring 53 connected to the pin 34. The lower end of this lever is provided with a forwardly projecting lug 54 which extends beneath the lower end of the coin slot.

Another lug 55 on the lever 51 extends through an opening 56 in the rear wall of the chute.

When a coin is forced downwardly from the operative position, it will be arrested by the lug 55 and a cooperating shoulder 57 formed on the opposite edge of the coin slot. When another coin is similarly forced downwardly from operative position, it will engage the coin on lug 55 and shoulder 57 and force it downwardly to the lowermost position in the chute where it will be 10 temporarily retained by the lug 54 and a shoulder 58 on the opposite edge of the chute. When still another coin is inserted and then forced downwardly from operative position, the lowermost coin will be forced from the chute into the 15 usual receiving magazine (not shown).

The improved actuating means for manually actuating the operating mechanism hereinbefore described includes an external handle 59 having an integral hub 60 journaled in a bushing 61 20 which is secured to the right-hand wall 4 of the casing by screws 62.

Located within the casing, is an arm 63 which is clamped to the hub 60 of the handle by a bolt 64. In order to secure the arm 63 and handle 59 25 against relative turning, the hub 60 has a pair of inwardly extending lugs 65 which engage apertures 66 in the arm. On the rear edge of the arm 63, is a hook 67 engaging a spring 68 which is connected to the casing for normally holding the arm 63 against a stop 69, thereby holding the operating handle 59 in the vertical position shown in Fig. 3.

Formed on the arm 63, is a pair of bearing lugs 35 or ears 70 which supports a pivot pin 71 on 40 which is pivotally mounted an actuating member 72 having a substantially flat face 73 adapted to engage the pin 15 of the bell crank 7 for actuating the operating mechanism. In order to cushion the impact of the member 72 against the pin 15, a heavy cushioning spring 74 is interposed between opposed faces of the member 72 and the arm 63. This spring is secured against displacement by bosses 75 formed on the arm 45 and actuating member.

Formed in the actuating member 72, is a recess 76 in which is located a detent 77 which is pivotally secured to the actuating member by a pin 78 located adjacent the upper wall of the recess. This detent is normally held by gravity in the 50 position shown in Figs. 3 and 4. Mounted on the casing is a stop 79 located adjacent the path of the free end of the detent 77. The positions of the stop 79 and detent are such that, when the handle 59 is operated in a normal manner the 55 detent will lie against the lower wall of the recess 76 and its free end will clear the stop 79.

Some unscrupulous persons who operate these machines, move the handle quickly in an attempt to cause the lug 19 of the bell crank 7 to jump 60 the notch 18 of the latch before the latch can be shifted to locking position by the spring 20. If such an attempt is made with this improved machine, the detent 77 will be shifted to the upper portion of the recess 76 as shown in dotted 65 outline in Fig. 4, and, in this position, its free end will extend forwardly sufficiently to engage the stop 79 when the actuating member is rocked.

The operation of the machine and the advantages of the improved actuating means are believed apparent from the foregoing description.

Although but one specific embodiment of this invention has been herein shown and described, it will be understood that details of the construction shown may be altered or omitted without de- 75

parting from the spirit of the invention as defined by the following claims.

I claim:

- 5 1. In a coin-controlled machine, the combination with a casing, of operating mechanism therein, a latch for said mechanism, coin-controlled means for disabling said latch to permit the operation of said mechanism, an external handle, an arm connected to said handle and located within the casing, an actuating member for said mechanism, said member being pivoted on said arm, and a cushion spring interposed between said member and a portion of said arm.
- 10 2. In a coin-controlled machine, the combination with a casing, of operating mechanism therein, a latch for said mechanism, coin-controlled means for disabling said latch to permit the operation of said mechanism, an external handle journaled on said casing, an arm located within said casing and fixed on said handle, an actuating member pivoted on said arm for actuating said mechanism, and a cushion spring bearing between said member and a portion of said arm for cushioning the impact of said member against said operating mechanism.
- 15 3. In a coin-controlled machine, the combination with a casing, of operating mechanism therein, a latch for said mechanism arranged to permit a limited movement of said mechanism, coin-controlled means for disabling said latch to permit the complete operation of said mechanism,

an actuating member movably mounted within said casing for actuating said mechanism, an external handle for said actuating member, a stop located adjacent the path of movement of said member, and a detent pivotally mounted on said member in position to clear said stop during the normal operation of said member but being adapted to be shifted outwardly into position to engage said stop when said actuating member is initially moved above a pre-determined speed.

5 10 4. In a coin-controlled machine, the combination with a casing, of operating mechanism therein, a latch for said mechanism arranged to permit a limited movement of said mechanism, coin-controlled means for disabling said latch to permit the complete operation of said mechanism, an external handle journaled on said casing, an arm connected to said handle and located within said casing, an actuating member pivoted on said arm and movable thereby through a predetermined path for actuating said mechanism, a cushion spring interposed between said member and arm, a stop located adjacent the path of said member, and a detent pivotally mounted on said member in position to clear said stop during the normal 15 20 25 operation of said member but being adapted to be shifted outwardly into position to engage said stop when said actuating member is initially moved above a predetermined speed.

BURNS S. WATLING.
